INVENTORS.

UNITED STATES PATENT OFFICE.

EDWARD SNYDER AND ISRAEL ADAMS, OF WORCESTER, MASSACHUSETTS.

COMBINED LATCH AND LOCK.

SPECIFICATION forming part of Letters Patent No. 236,189, dated January 4, 1881.

Application filed October 1, 1880. (Model.)

To all whom it may concern:

Be it known that we, EDWARD SNYDER and ISRAEL ADAMS, both of Worcester, in the county of Worcester and State of Massachusetts, have invented certain new and useful Improvements in Door Latches and Locks; and we declare the following to be a description of our said invention, sufficiently full, clear, and exact to enable others skilled in the art to 5 to which it appertains to make and use the same, reference being had to the accompanying drawings, which form a part of this specification, and in which—

Figure 1 is a sectional view of a portion of a door with our improved latch and lock applied thereto, the devices being shown in side view with the side plate of the latch-case removed. Fig. 2 is a vertical transverse section at the position indicated by line xx , Fig. 1. Fig. 3 is a horizontal sectional view through the latch-case and knob-spindle. Fig. 4 is a horizontal sectional view, showing the locking-bolt. Fig. 5 shows the form of the key, and Fig. 6 shows the key-hole plate.

The object of our invention is to make a cheap, serviceable, and secure latch and lock adapted for use on the doors of buildings; and our invention consists in mechanism constructed and organized as shown in the accompanying drawings, and applied to use as herein described, the particular subject-matter claimed being definitely specified.

A denotes the door; B, the face-plate; C, the latch-bolt, arranged within a cylindrical case, B', fastened to the face-plate B.

D indicates the follower, through which the knob-spindle E passes, and by means of which the latch-bolt C is drawn back when the knob is rotated. The follower D is connected to the rear end of the latch by a link, F, one end of which is attached by a pin, d, to the side of the follower D, and its other end looped over a pin, e, at the rear end of the latch-bolt C, as illustrated. A spring, G, is provided for throwing the latch-bolt C forward in the ordinary manner.

H indicates the lock-bolt, arranged below the latch-case, and working through an opening in the face-plate B. Said lock-bolt is of cylindrical form and runs directly in the wood A, without other casing. It is provided with a slot in its upper side, into which a spur or

projection, e, on the latch-case extends, and serves to prevent the bolt H from working out of proper position. A space or recess, i, is 55 formed on the under side of the bolt for the bit of the key to enter.

Working within a suitable slot, l, near the rear end of the bolt H, is an arm, f, which extends down from the follower-link F in the 60 manner shown. This arm serves to throw forward the lock-bolt H by the latch action. The slot l, when open, lets the arm f move back without drawing the bolt H. A spring, J, is fixed to the side of the bolt to give friction 65 for retaining the bolt from jarring out of adjustment.

L is a thumb-knob for moving the bolt by hand at the inner side of the door.

The key K is made, as in Fig. 6, with the bit 70 centrally recessed to fit the ward in the recess i of the bolt. Variation can be effected by changing the form of the ward and recess i.

The key-hole I is made in the shape shown in Figs. 1 and 7, and is formed by boring the 75 hole I through the wood of the door, then sawing kerfs or slots m m to the right and left. The wood is then taken out above the kerfs to the bolt-recess. The lower side of the key-hole is on the solid wood, and the key is entered 80 with the bit either to the right or left, according to the direction in which it is desired to move the bolt H.

The lock and latch are applied to the door by boring two auger-holes, M N, into the edge 85 of the door at proper distance apart, then boring transversely through for the key-hole and knob-spindle, also the space for the thumb-knob L. The wood between the holes M N is removed for a narrow space along the 90 center, as at P, and the face-plate mortised into the edge of the door.

It will thus be seen that the labor of applying the lock and latch to the door is very slight, comparatively, while the wood of the 95 door is but little cut away.

It will also be observed that the wood of the door serves in lieu of a case for the lock, that the mechanism is simple and cheap of application, while its effect in operation is that of 100 a secure dead-bolt or night-lock. The door is locked by the latch or knob, but requires to be unlocked by means of the key or the inside thumb-knob L.

What we claim as of our invention, and desire to secure by Letters Patent, is—

1. The combination, with the cylindrical latch-case, provided with the face-plate, latch-bolt, and latch-operating mechanism, of a locking-bolt adapted to be let into a cylindrical opening directly in the wood of the door and arranged for locking by a movement of the latch mechanism, substantially as set forth.

15 2. The bolt H, having recesses and ward i, and friction-spring J, as described, in combination with the door provided with the cylindrical opening or auger-hole N and the key-hole recess I m, formed substantially as set forth.

3. In combination, substantially as described, the cylindrical case B', having face-plate B and guide-lug e, the latch-bolt C, the follower D, the link F, with arm f, and the locking-bolt H, having key-recess i and slot to engage the lug e and arm f, said parts being constructed and arranged for operation as shown and for the purpose set forth.

Witness our hands this 28th day of September, A. D. 1880.

EDWARD SNYDER.
ISRAEL ADAMS.
